ABSTRACT: A method and apparatus for correction of texts for use in photographic composing machines involving identifying the lines of the text in clear form and on perforated tape, placing the corrected lines with identification on perforated tape, and substituting corrected lines for original lines with same identification sign through use of coincidence detector connected to both the original tape reader and the corrected tape reader. When lines are eliminated or added, a sequence counter reestablishes logical sequencing of the lines on the revised text. Identification signs can then be removed and the text, in clear form, used in photographic composing machines.

PHOTOGRAPHIC COMPOSITIONS

The present invention relates to improvements in photographic composition and the automatic correction of texts designed for publishing or printing through the use of high speed photographic composing machines.

At the present time, correction of the composition is carried out, generally and whatever the composing machine, on the basis of a text "in clear" in the type written form proceeding from a servo writing machine or a so-called "rapid printing" machine. The author has not, in order to make his corrections or suggestions, a clear text which is the exact reflection of the definitive text both as regards the types employed and the presentation, justification, body, style of the types, etc.

Now, the present invention precisely proposes to provide the author with a clear proof which is the most faithful possible reflection of the definitive text. However, the invention aims at making use of this clear proof to permit, automatically, the correction of the recording strip which served for the production of said proof.

The production of this proof is obviously only possible, economically, due to the existence of composing machines working at great speed and in particular because of photographic composing machines as well as due to the improvements in the films and sensitive paper used in these machines.

In accordance with the method of the invention, the composition of the text itself is first made on a recording strip (by example, a perforated strip following a determined code). This codified perforation may be made either by means of a so-called "blind" keyboard, that is to say, a keyboard which does not permit the visual control of the corresponding operation at each key acted upon, or by means of an "informed" conventional keyboard, which permits such visual control.

In the case of a correction on a film, the problem consists in identifying each of the lines of the composed text. The methods at present known do not permit such an identification in an automatic manner. They do not permit of the identifying of lines on a proof which is the faithful representation of the text as it will finally appear. Moreover, they cannot guarantee the exact localization of the corrections to be effected. Further, users are often obliged to count the lines, which is a source of errors without excluding those resulting from a fault in the concordance between the witness copy and the codified strip.

Both on the clear text and on the codified strip, the method according to the present invention consists in causing to appear, automatically, at the beginning and the end of the line, signs of identification of the line.

This demand for identification of the line occurs, in accordance with the invention, at the moment when the operator actuates the "end of line" key or the return of the carriage.

The identification of the line is carried out in particular by any specially distinctive sign and particularly through numerical identification. This latter identification method has furthermore the advantage, when it is utilized, of permitting the counting of the lines.

The method of the invention may be applied to any photographic composing machine without necessitating any modifications whatsoever in the mechanism of said machine.

Due to the invention, one disposes of a sure means, avoiding any error. Indeed, by the numerical identification of the lines of the initial text being faithfully reproduced on the so-called correction strip, there cannot be any risk of confusion of the lines to be corrected. In addition, the possibility of counting these lines by their order number not only avoids a hazardous setting of the line of the text comprising the corrections but also gives an idea of the importance of the composition. There results great working simplicity not necessitating any initiation of the operator to novel work, his sole requirement being, when he proceeds with the setting up of a so-called correction strip, to reproduce the identification sign existing at the beginning and end of each line. Moreover the operator may ignore that it is a matter of a particular sign, since his role is to reproduce faithfully any sign or type presenting itself at the beginning or end of the text to be corrected.

In accordance with the invention, there is included a means permitting, automatically for each call for the so-called "end of line" key of the keyboard, of actuating the recording device so that the latter causes to appear on the recording strip an identification sign and/or on the film if the keyboard is mounted directly on the composing machine.

According to another characteristic of the invention, the identification signs of the lines follow each other in logical order.

Other advantages and characteristics of the invention will be more clearly apparent from the description which follows with reference to the accompanying drawings in which:

FIG. 1 shows a proof of an initial text with notes by the author;

FIG. 2 shows the corresponding recording strip (perforated strip according to a code);

FIG. 3 shows the proof of the corrected lines;

FIG. 4 shows the recording strip corresponding to FIG. 3;

FIG. 5 shows the strip corresponding to the corrected text;

FIG. 6 being the reflection "in clear";

FIG. 7 shows the diagram of the "strip mixer" system employed for correction; and

FIG. 8 shows the diagram of a system permitting the automatic identification of the lines of a text to be composed.

Referring to these FIGS., FIG. 1 shows an initial text obtained by photocomposition from a recording strip (FIG. 2) comprising, after each code illustrating the "end of line" sign, an identification code, which, in the present case, is a numerical identification code. This code is designated by the references 1 and 2, which correspond to the numerations 01, 02, 03, etc. figuring on the proof shown in FIG. 1. On this proof, the author makes the desired corrections as shown. At the reading of this marked proof, the operator reproduces, on

5 a fresh recording strip, the lines comprising the corrections taking care to reproduce these lines integrally, that is to say, with their identification signs. He thus obtains a strip such as shown in FIG. 4 which, if it were reproduced directly, would give a proof such as shown in FIG. 3. The author can thus ascertain how these corrections will affect the aspect of the line or its appearance.

From the initial recording strip and the so-called correction recording strip, it is then possible to produce a definite or "intermediate" text by causing the two strips to progress simultaneously in a device such as the one which will be described hereafter which, when it signals a "coincidence" will reproduce the elements provided by the so-called correction strip until such "coincidence" ceases, to return to the initial recording strip and so on.

55 Such a device has conventional components. It will suffice, with reference to the diagrammatic FIG. 7, to indicate the main organs or components with which it is composed as well as the manner in which they work together.

This device comprises a first reader 3 so-called original reader, a second reader 4 so-called correction strip reader, a coincidence detector 5, a perforator or recorder 6 providing, through the elements given by the readers 3 and 4, the so-called corrected strip and finally a meter 7, the role of which will be indicated hereafter.

55 The above device operates in the following manner: The initial recording strip advances in front of the reader 3. In the course of this advance, this reader 3 transmits to the recording device 6 the information read. Recording device 6 produces a codified strip which may be perforated as in the example illustrated. The correction strip is in waiting position under the reader 4. When the identification sign figuring on the correction strip is the same as the one figuring on the initial strip, the coincidence detector 5 acts so as to stop the

65 reading of the device 3 to start that of the device 4. The correction strip advances in front of the reading device 4 while the initial strip adopts a waiting position. The device 6 continues to play its role due to the elements provided by the reader 4. These elements, as moreover those provided by the reader 3, are at the same time taken over by the meter 7 which

reestablishes automatically the logical sequence of the identifications. One, in fact, understands the necessity of the presence of such a counting device 7 to reestablish this logical sequence in the event of the author eliminating or adding lines to the initial text which has been presented before him and so that these lines be correctly identified relative to the lines which have remained unchanged and are already carrying their own identification. To this end, the correction strip comprises, in the case of the addition of lines, either a code chosen for this purpose or the pure and simple repetition of the identification code of the line immediately preceding the line to be added. For the line to be eliminated, the strip generally comprises a particular code for this purpose.

The system permitting the automatic identification of the lines of a text to be composed is the one shown in FIG. 8. It is constituted by a step by step electromechanical selector 8-9 or an electronic device with bistable stages furnishing its information to one or several corresponding codification devices 10-11. This selector device is connected through 12 to a code distributor 13 which influences successively and in order, the device 14 corresponding to the end of line code, the devices 15 and 16 corresponding to the code of tenths and units and the device 17 corresponding to the "fixed space" code. It may also influence, if necessary, the devices 21 and 22 corresponding to the codes of the "capital" and "small" functions. Finally, the distributor 13 influences the line 18 proceeding to the perforator or any other recording device. The selecting device 8-9 comprises the unit stages I, II, III ... X connected to the device for the codification of the units 10 and the stages of the tenths I, II, III ... X which begin to be demanded when the last stage of the units has been "reached." These tenths stages are connected to the device for the codification of the tenths 11.

One will therefore understand that each time that the end of line key is activated, there is produced a signal which passes through the code distributor 13 which will first of all translate this signal into an end of line code 14. Through the line 12, this signal will be transmitted to one of the unoccupied stages of the selector 8-9, which is interpreted, through the agency of the devices 10-11, by the dispatch of a code of tenths 15 and units 16. If no stage of the tenths is yet influenced (beginning of an operation), the first code of tenths is interpreted generally by the number zero (0). This explains that in FIGS. 1 to 6 each of the ten lines is given a numerical identification sign beginning by zero. The code distributor 13 finally sends a signal for codification, through 17, of a so-called "fixed space" space for example, one or several *em* quadrants, which is shown in FIGS. 1 to 6 by a blank space, the presence and signification of which will be explained hereafter.

If need by, the apparatus schematized and shown in FIG. 8 may be completed by luminous indicators 19 and 20 respectively connected to the devices 10-11 and which, at each activation of said devices, notes the corresponding result in front of the eyes of the operators; that is to say, it clearly gives him the identification number of the line which is about to start. It is obvious that one may use as many stage columns as one desires depending upon the identification signs. That is to say, that the identification may comprise several decimal rows and go up to 99, 999, 9999, etc.

The reason why a fixed free space has been provided is the following:

When the author has given his agreement to the text

presented, the final proof which will serve for the making of the plates will be passed under a suitable apparatus cutting along line A-B of FIG. 6 of the proof in question, so as to remove all the identification signs which have no more reason to exist, since there are no longer any corrections to be effected, and the said identification signs are there only to assist in the corrections.

The system shown in FIG. 8 is a known system of impulse counting connected for use in the manner described with the apparatus of the present invention. It is here of interest for the automatic working which it permits for the identification of the lines of a text which may be submitted to correction.

It is obvious that the present invention has been described only in an explanatory but by no means limitative manner and that any useful modifications may be made therein without departing from its scope.

I claim:

1. The method of correction of texts to be composed involving photographic composition comprising the steps of:
  - 20 producing a text in a printed clear form;
  - 25 simultaneously producing said text in a codified strip form; inserting an identification signal at each line of said clear and codified texts;
  - 30 correcting said printed clear form of the text;
  - 35 reproducing corrected lines of said text in at least codified form with the identification signal of that line location in the original text thereon;
  - 40 reading with a first reader the original text in codified strip form having identification signals corresponding to each line of the text in printed clear form;
  - 45 reading with a second reader the corrected lines of said text in codified form with said identification signals corresponding to that line of original text; and
  - 50 detecting and reproducing a revision of said text in at least clear form by replacing with corrected lines in codified form the lines having the same identification signal on said original codified strip form.
2. The method of claim 1 further characterized by said inserting of an identification signal takes place with the actuating of an end of line signal.
3. The method of claim 1 wherein said identification signal is a numerical sign.
4. The method of claim 1 further characterized by:
  - 45 said identification signal at each line of said clear text being a numerical sign; and
  - 50 the additional step of removing said numerical signs from the last produced revised text in preparation for photographic composing and reproduction of said revised clear text.
5. The method of claim 1 further characterized by the step of determining coincidence of identical identification signals on both codified forms in order to substitute the codified form of corrected lines for the same lines of original codified text.
6. The method of claim 5 further characterized by stopping the reading of the original text in codified strip form upon detecting coincidence of identical identification signals in the codified form of the corrected lines of the text to record the reading of said corrected line of text in codified form.
7. The method of claim 6, further characterized by
  - 60 reestablishing logical sequence of the identification signals during said recording while both eliminating and adding lines of text.
